Filed Aug. 13, 1962, Ser. No. 216,657
6 Claims. (Cl. 182—134)

This invention relates to devices for climbing structural members such as I-beams, channels, and the like, and represents an improvement over the climber disclosed in my Letters Patent No. 3,019,852.

It is the principal object of the present invention to provide a climber of the class described which is releasably engageable with a structural member with facility and precision, affording maximum security of support.

Another important object of this invention is the provision of a climber of the class described which is of simplified construction for economical manufacture.

The foregoing and other objects and advantages of this invention will appear from the following detailed description, taken in connection with the accompanying drawing in which:

FIG. 1 is a plan view of a climber embodying the features of the present invention;

FIG. 2 is a sectional view taken along the line 2—2 in FIG. 1;

FIG. 3 is a fragmentary enlarged view in side elevation, as viewed along the line 3—3 in FIG. 1, showing the pivotal mounting of the outboard shoe strap anchor, a portion being broken away to disclose details of internal construction;

FIG. 4 is a fragmentary enlarged sectional view taken along the line 4—4 in FIG. 1;

FIG. 5 is a sectional view taken along the line 5—5 in FIG. 1;

FIG. 6 is a sectional view taken along the line 6—6 in FIG. 1; and

FIG. 7 is a plan view showing a pair of climbers in operative engagement with the projecting flanges of an I-beam, the cooperative positions of the associated shoe soles being illustrated by dot and dash lines.

The climber of the present invention includes a laterally elongated mounting plate 10 adapted for attachment to a shoe transversely across the sole 12 with its rearward edge in abutment with the forward edge of the heel 14 (FIG. 7). The mounting plate may be secured to the shoe by various means. In one embodiment illustrated, the securing means includes a pair of laterally spaced rings 16 and 18 adapted to engage a strap (not shown) which extends across the upper side of the shoe and thence rearward around the back of the shoe, in manner which will be apparent.

The outboard ring 16 is of generally rectangular configuration, and it is installed on the mounting plate initially by slipping the latter through the ring by disposing the ring diagonally with respect to the plate. The inner length 16' of the ring is circular in cross section, and is received rotatably within a groove 20 formed in the plate adjacent the outer end thereof between the front and rear margins of the plate. The outboard portion 10' of the plate defining the groove then is swaged or otherwise bent inward to partially constrict the open bottom side of the groove, whereby to retain the ring

2

therein. In this manner the ring may be rotated between a folded position in which its outer length rests upon the mounting plate, as indicated by the dot-and-dash lines in FIGS. 1 and 2, and an extended position projecting upward from the plate. Continued outward rotation of the ring preferably is restricted as by means of the fore and aft extensions 22 on the terminal portion 10' of the plate.

The inboard ring 18 is of the same configuration as 10 the outboard ring, and its inner length 18' is mounted rotatably in the fore and aft groove 24 provided in the plate adjacent the inboard end of the latter. Swaging or other bending of the plate defining one side of the groove effects constriction of the open end of the latter to confine the ring rotatably therein.

Straps are attached to the outer lengths of the rings for wrapping about a shoe, as previously described. The upper surface of the mounting plate preferably is roughened, as by the knurling illustrated, to insure positive gripping of the sole of the shoe.

Alternatively, the strap rings 16, 18 and knurling may be omitted and the mounting plate 10 bonded integrally with the shoe sole 12 when the latter is made of rubber or other moldable material. This may be achieved, for example, by embedding the plate in the moldable shoe sole during manufacture of the latter. A plurality of holes 26 preferably are provided in the plate for passage of the moldable material therethrough, to join the material on both sides of the plate. Thereafter, the sole may be shaped and integrated with a shoe, and the heel attached, in accordance with general practice.

The inboard end of the mounting plate 10 is integrally attached to a gripper head 30, as by casting or otherwise forming the plate and head as a single piece. The head extends laterally outward from the mounting plate, and preferably inclines angularly upward from the plate to elevate the outer portion of the head from the inner portion.

The head is provided with a recess 32 intermediate its inner and outer ends. The recess extends in the fore and aft direction of the head, opening onto the forward end of the latter and terminating forwardly of the rearward end of the head. The recess thus defines a pair of laterally spaced, forwardly projecting jaws 34 and 36. The defining side surfaces 34', 36' of the recess are angled obliquely downward toward the outboard end of the head, thus forming with a plane extension of the mounting plate 10 an included angle of less than 90°. In this manner there is provided a sharp bottom edge 38 on the inboard jaw 34 and a sharp top edge 40 on the outboard jaw 36, spaced vertically with respect to each other and adapted to receive between them the flange 42 of a structural member 44.

In the preferred embodiment illustrated, the cooperating gripping edges 38 and 40 of the jaws are provided with spaced teeth, in the form of transverse notches, designed to enhance the ability of the edges to grip the structural member. To this end the forward edge 46 of each notch forms with the adjacent jaw edge an included angle of not more than 90°, and the rearward edge 48 of each notch forms with the adjacent jaw edge an included angle greater than 90°. The gripping edges of the jaws thus tend to penetrate the engaged surface

of the flange 42, thereby inhibiting retraction of the head 30 from the flange.

In order to accommodate structural members having projecting flanges which taper in thickness toward their outer ends, the gripping edge of one of the jaws, preferably the outboard jaw 36, is curved arcuately outward through a portion of its forward length. The recess 32 thus flares to wider dimension at its forward end to accommodate the taper of a flange. If the flange is of uniform thickness, as indicated at 42' by the dotted lines in FIG. 1, the inner portion of the gripping edge on the outboard jaw provides the engagement.

The inboard jaw 34 preferably extends forward beyond the outboard jaw, and the outer portion of the gripping edge 38 is curved arcuately forward in the inboard direction, to further increase the forward opening to the recess 32. The inboard edge 34" of the forward portion of the inboard jaw also is curved arcuately forward in the outboard direction from a point adjacent the inboard end of the mounting plate 10. As best illustrated in FIG. 7, this arcuate edge 34" conforms to and lies close to the adjacent edge of the shoe sole 12 in the instep area of the shoe, permitting the forwardly projecting edge 12' of the sole to form an effective extension of the forward gripping edge 38 of the inboard jaw. Accordingly, the forwardly projecting inner edge of the shoe sole serves to guide the flange of the structural member properly into the recess 32, as explained more fully hereinafter.

It will be observed, from FIGS. 1 and 7, that the transverse axis of the mounting plate 10 is disposed at a slight angle with respect to the inboard gripping edge 38. That is to say, the included angle between the transverse axis of the mounting plate and the inboard gripping edge is slightly greater than 90°. This is provided because of the slight angular disposition of the forward edge of a conventional shoe heel 14 with respect to the longitudinal axis of the shoe. The slight angular offset between the mounting plate and inboard gripping edge thus disposes the latter and hence the longitudinal axis of the recess 32, substantially parallel to the longitudinal axis of the shoe. Accordingly the feet may remain parallel with the sides of a structural member during climbing.

Additionally, referring particularly to FIG. 6, the mounting plate 10 preferably is disposed in a forwardly inclined position relative to the base surface of the head 30, to conform to the general slope of the under surface of the shoe sole in the area immediately forward of the heel. The mounting plate also preferably tapers to reduced thickness in the forward direction to minimize the thickness of the forward edge and thus minimize accidental stubbing of said edge against objects on the ground during normal walking.

The climber described hereinbefore is used pairs, one for each foot, as illustrated in FIG. 7. With the pair of climbers secured to the shoes, as by either of the securing means described hereinbefore, the workman approaches the structural member 44 to be climbed and encircles the latter with his conventional safety belt. The workman then lifts one foot and moves it forward along the outer side of the structural member, with the sole of the shoe substantially horizontal. The inside edge 12' of the shoe may be slid along the outer side of the structural member, whereby to guide the projecting flange 42 positively into the recess 32 in the climber head 30. In this manner the workman need not look downward to visually align the flange 42 with the recess, since the alignment is achieved automatically by the guiding edge formed by the inner side edge 12' of the shoe sole and the outer forward edge 38 of the inboard jaw 34. The inner edge of the shoe sole is positioned closely adjacent the inboard edge 34" of the forward portion of the inboard jaw. Accordingly, the possibility

of inadvertently bringing the projecting flange 42 of the structural member between the shoe sole and inboard jaw is substantially eliminated, with consequent elimination of the hazard attending failure to align the flange with the gripping edges 38, 40.

Having thus properly inserted the flange 42 into the recess of the climber head, the workman then rocks his foot slightly outward and downward to cause engagement of the opposed gripping edges 38 and 40 of the jaws with the opposed surfaces of the flange. The workman then can impose his weight upon that climber, enabling him to step upward from his former position. The foregoing procedure then is repeated alternately for each foot, whereby the workman is enabled to climb the structural member substantially with ease of climbing a stairway.

Referring particularly to FIG. 2 of the drawing it will be observed that the low profile of the climber accommodates storage in a minimum of space. This minimum profile is preserved even when the strap rings 16, 18 are employed, since the latter may be rotated to the collapsed positions illustrated by the dot-and-dash lines. This pivotal mounting of the rings also permits them to conform closely to the adjacent sides of the shoe as the securing strap is tightened, thus minimizing lateral displacement of the climber relative to the shoe.

Although the climbers are shown in FIG. 7 to be mounted in such manner that the gripping heads 30 are positioned on the insides of the shoes, it will be apparent that the climbers may be designed to position the gripping heads on the outside of the shoes for use in climbing structural members which accommodate such an arrangement. In such event it may be desirable to arrange the head 30 relative to the mounting plate 10 such that the angle included between the transverse axis of the mounting plate and the gripping edge 38 of the inboard jaw 34, is slightly less than 90°, so that the inboard gripping edge will be parallel to the longitudinal axis of the shoe.

It will be apparent to those skilled in the art that various other changes may be made in the details of construction described hereinbefore without departing from the spirit of this invention and the scope of the appended claims.

Having now described my invention and the manner in which it may be used, what I claim as new and desire to secure by Letters Patent is:

1. A climber device for use with foot gear for climbing a flanged structural member, comprising an elongated mounting plate adapted to be secured to a shoe and to extend transversely with respect to the shoe, a gripping head extending laterally outward from the mounting plate and having therein a forwardly open recess defining laterally spaced inboard and outboard jaws, the inboard jaw extending forwardly of the mounting plate, the bottom outer edge of the inboard jaw being positioned a spaced distance below the upper inner edge of outboard jaw, said edges defining gripping edges to receive the flange of a structural member therebetween and to grip the latter at vertically spaced points, means on the mounting plate for securing the latter on a shoe with the inner edge of the inboard jaw positioned adjacent the shoe sole edge, the forward end of the inboard jaw terminating substantially at a point with the forward end of the outer edge of the inboard jaw terminating adjacent the shoe sole edge, whereby the outer edge of the inboard jaw forms with said adjacent shoe sole edge a guide edge for guiding a structural member flange into said recess.

2. The climber device of claim 1 wherein the forward end portion of the gripping edge of one of the jaws is curved arcuately away from the recess to accommodate in the recess a tapered flange of a structural member.

3. The climber device of claim 1 wherein the forward end portion of the gripping edge of the outboard jaw is curved arcuately outward to accommodate in the recess a tapered flange of a structural member.

4. The climber device of claim 1 wherein the securing means comprises shoe strap supports mounted pivotally adjacent the outboard and inboard ends of the mounting plate for folding inwardly toward the center of the mounting plate.

5. The climber device of claim 1 wherein the mounting plate has a rearward heel-abutting edge and is tapered forwardly therefrom to substantially less thickness at the forward edge.

6. The climber device of claim 1 wherein the mounting plate and head are disposed relative to each other so that the longitudinal axis of a mounted shoe and the forwardly extending recess are substantially parallel.
